UNITED STATES PATENT OFFICE.

EDWARD H. BRUNE, OF ST. LOUIS, MISSOURI.

MAGNETIC SEPARATOR.

Application filed January 28, 1926. Serial No. 84,389.

The present invention consists of a magnetic separator and is designed as an improvement over my prior Patent Number 1,539,640 issued May 26, 1925.

An object of the invention is to provide a separator of this character which is especially adapted for use in the removal of metallic elements, such as broken picks, bolts, washers, etc., from coal without crushing the lumps of coal, yet positively removing even the minutest metallic particle which may have found its way into the coal during mining or subsequent to having been mined.

A coordinate object of the invention is to utilize a magnetic cell of considerable density which may be made in sections to facilitate assemblage and transportation and which is capable of exerting sufficient magnetic influence to pick up metallic bodies of relatively large size and great weight.

Other objects of the invention will be apparent from the following description of the present preferred forms of the invention as illustrated in the accompanying drawings, wherein:—

Fig. 1 is a longitudinal sectional view of a magnetic separator constructed in accordance with the present invention illustrating its application;

Fig. 2 is an end elevational view of the baffle used in the present invention;

Fig. 3 is a detail fragmentary side elevational view of the separator drum and a sectional view of a slightly modified form of baffle; and

Fig. 4 is a cross sectional view of the separator.

In the drawings, for the purpose of illustrating the application of the present invention a supporting structure 5 is shown which has a pair of standards 6 mounted thereabove in which the ends of a shaft 7 are revolvably mounted. One end of the shaft 7 is equipped with a pulley 5 which is adapted for the reception of a power belt for the purpose of rotating the shaft 7. A pulley wheel 9 is rotatably mounted on the support 5 and has a conveyor belt 10 trained thereabout, the belt being arranged to travel beneath the shaft 7.

Loosely mounted on the shaft 7 is a magnetic body generally designated 11 which in the present instance consists of a series of solid segments 12 which are secured together so as to remain in contiguity and are an-

chored on one of the standards 6, as indicated at 13. It is desired that the magnetic segments 12 be so positioned that their concave faces 14 are at one side, as shown in Fig. 4 of the drawings for a purpose hereinafter set forth. A drum or shell 15 made of brass or like material is revolvably mounted on the magnetic body 11 and is fixed to the shaft 7 in any desired manner so that rotation of the shaft imparts corresponding movement to the drum. In Fig. 1 of the drawings the drum is indirectly connected to the shaft by virtue of a baffle 16 which is sleeved on the shaft 7 and is fixedly secured thereto, the baffle in turn being fixedly secured to the drum, as indicated at 17. Consequently, as the shaft 7 rotates, the baffle 16 and drum 15 are concurrently rotated. The baffle in the present instance is shown to be of semi-elliptical shape in cross-section and has the marginal edge thereof projected over one end of the drum 15. By preference, the drum tapers and the baffle encases the smaller end of the drum so that lumps of coal and other materials conveyed by the belt 10 will be deflected to prevent contact thereof with the magnetic body 11. Moreover, the baffle is designed to deflect lumps of coal to the sides of the drum eliminating the possibility of the lumps being ground beneath the drum. The belt is of sufficient width to permit the lumps to be carried along the sides of the drum and ultimately dumped over the pulley wheel 9. The larger metallic particles will be taken up by the smaller end of the drum while the smaller particles will be taken up by the larger end of the drum which operates in close proximity to the upper surface of the belt 10.

To eliminate the possibility of the drum 15 being depressed inwardly at the concave side of the magnetized body 11, suitable bracing elements 18 are provided. These elements may consist of metal bars secured to the concave face of the magnetic body 11, as illustrated to advantage in Fig. 4.

If desired, the drum 15 may be directly connected to the shaft 7, as indicated at 19, and where this form of invention is employed the baffle 16 is fixedly connected to the standard 6, as indicated at 20.

In use of this device the drum 15 is rotated by the application of power to the pulley 8. The materials, such as coal, or the like, are deposited on the belt 10 and permitted to

travel against the baffle 16 which latter, as above described, may be stationary or revoluble with the drum. The materials, by reason of the movement of the belt 10 will be carried either beneath the drum 15 or alongside of the latter so that metallic elements will be intercepted by the drum. The elements or particles thus intercepted are carried up over the top of the drum but are permitted to gravitate therefrom when the part of the drum carrying the metallic elements or particles reaches the concave side of the magnetized body 11. At this particular point the drum is demagnetized and is consequently removed of any metallic bodies, although, if desired or found necessary, a scraper, such as used in my issued Patent Number 1,539,640, may be used.

While I have herein described only the preferred forms and a preferred use of this invention, I am aware that the invention is capable of other modifications and susceptible of a variety of uses within the scope of the claims hereto appended.

25 What is claimed is:—

1. In combination with a movable coal carrying belt, a magnetic separator including a drum mounted above the belt and equipped with a baffle to divert lumps of coal away from the drum.

2. In combination with a movable coal

carrying belt, a magnetic separator including a drum mounted above the belt and a baffle positioned in advance of the drum to divert lumps of coal to the sides of the drum. 35

3. In combination with a movable belt for carrying materials, a magnetic separator for removing metallic bodies from said materials including a magnetized drum mounted above the belt and engageable with said materials, and a baffle mounted adjacent the drum to prevent materials from contacting with the end of the latter. 40

4. In combination with a coal carrying belt, a magnetic separator including a tapering drum rotatably mounted above the belt and having its longitudinal axis arranged parallel to the longitudinal axis of the belt, and a baffle carried by the smaller end of the drum to deflect the coal from contacting 50 with said end.

5. A magnetic separator including a drum and power shaft extending through said drum and secured thereto, and a magnetic body mounted on the shaft within the drum and provided with a concavity, and brace elements mounted in said concavity and engaged with said body and drum to prevent depression of the drum into the concavity. 55

In testimony whereof I affix my signature.

EDWARD H. BRUNE.
